(57) **CLAIM**

The ornamental design for a gynecological examination sheath, as shown and described.

DESCRIPTION

FIG. 1 is a left side elevational view of a gynecological examination sheath according to the present invention.

FIG. 2 is a right side elevational view of the gynecological examination sheath of FIG. 1.

FIG. 3 is a front elevational view of the gynecological examination sheath of FIG. 1.

FIG. 4 is a rear elevational view of the gynecological examination sheath of FIG. 1.

FIG. 5 is a top plan view of the gynecological examination sheath of FIG. 1.

FIG. 6 is a bottom plan view of the gynecological examination sheath of FIG. 1; and,

FIG. 7 is a three quarter view of the gynecological examination sheath of FIG. 1.

The dashed lines illustrate environment that does not form a part of the present invention, and no claim is made to the material illustrated with dashed lines.
